R. E. MAXWELL,
LOCOMOTIVE JOURNAL BOX MOUNTING.
APPLICATION FILED JULY 13, 1917.

Patented Mar. 26, 1918.

UNITED STATES PATENT OFFICE.

ROBERT E. MAXWELL, OF SAVANNAH, GEORGIA.

LOCOMOTIVE JOURNAL-BOX MOUNTING.

1,260,425.

Specification of Letters Patent. Patented Mar. 26, 1918.

Application filed July 13, 1917. Serial No. 180,438.

To all whom it may concern:

Be it known that I, ROBERT E. MAXWELL, a citizen of the United States, residing at Savannah, in the county of Chatham and 5 State of Georgia, have invented certain new and useful Improvements in Locomotive-Journal-Box Mountings, of which the following is a specification.

This invention relates to locomotive journal box mountings, and has for one of its 10 important objects to prevent looseness of certain parts of the mounting and to effect adjustments thereof to take up wear.

It is a common practice to employ flanged 15 shoes in the journal box opening, one shoe embracing one of the pedestals and the other shoe embracing the other pedestal. These shoes are loose when originally put 20 in place, and by reason of vibration, they wear the pedestals. It is an important object of this invention to prevent this looseness and thereby to prevent wear upon the pedestals. To accomplish this result, I provide a wedge member mounted in a groove 25 in the inner face of one of the flanges of each shoe, and I mount the wedge on the binder and provide for convenient adjustment of the wedge to take up wear.

As a general practice, the connection between the wedge shoe and the adjustable bolt has been a loose connection, and while the bolt itself may be rigid with the binder, the wedge is loose thereon and therefore capable of shaking under vibrations of the 35 journal box, resulting in wear upon the wedge and the frame to such an extent that frequent adjustments and renewals of the wedge are necessitated. According to the present invention, I preserve a detachable 40 connection between the bolt and the wedge-shoe, while at the same time I also maintain a rigid connection between the adjusting bolt and the wedge-shoe when the latter has been set to any adjusted position.

With these and other objects in view, the present invention consists in the combination and arrangement of parts as will be hereinafter more fully described, shown in the drawings, and particularly set forth in 45 the appended claims, it being understood that changes in the form, proportion, size and minor details may be made within the scope of the claims, without departing from the spirit or sacrificing any of the advantages of the invention.

In the drawings,

Figure 1 is a side elevation of a journal box frame and its binder having applied thereto the features of the present invention.

Fig. 2 is a sectional view on the line 2—2 of Fig. 1.

Fig. 3 is a plan view looking at the underside of the binder.

Fig. 4 is a fragmentary detail view showing the connection between the wedge and the adjusting bolt thereof.

Fig. 5 is a detail sectional view taken on the line 5—5 of Fig. 2.

Fig. 6 is a fragmentary detail perspective view of one of the wedge-shoes.

Fig. 7 is a detail sectional view on the line 7—7 of Fig. 1.

Like characters of reference designate corresponding parts in each of the figures of the drawings.

In Figs. 1 and 2 of the drawings, there have been shown the usual pedestals 1 and 2 of the journal box frame of a locomotive, and the binder 3 suitably secured across 80 the lower ends of the pedestals, say for instance by suitable fastenings 4 in the form of bolts extending through the binder and the lower portion of the frame. The pedestals 1 and 2, the binder 3 and the upper 85 horizontal member 5 of the frame define an opening 6 for the reception of a journal box in the usual manner. At one side of the journal box opening 6 there is a flanged shoe 7, said shoe embracing the pedestal 1 which 90 has a substantially vertical inner face, while a flanged wedge-shoe 8 embraces the inner face of the pedestal 2, which face is inclined upwardly and inwardly, as at 9. The parts thus far described are old and well known 95 and form in themselves no part of the present invention.

One of the features of the present invention is to prevent transverse looseness of the shoes, and this is accomplished by means of an upstanding wedge 10, one for each shoe. Said wedge is received within an upright groove or channel 11 formed in the inner face of one of the flanges of each shoe. By reference to Fig. 5 of the drawings, it will 105 be noted that the groove 11 is deepest at its lower end and tapers in depth upwardly. The wedge 10 has its outer face, or that face which engages the pedestal, straight and vertical so as to lie against the face of the 110 pedestal, while the inner face of the wedge is inclined in accordance with the inclina-

tion of the back wall of the groove or channel 11 in the flange of the shoe. The wedge is longer than the shoe and projects downwardly through the open bottom of the 5 groove 11 and has its lower end adjustably secured to a bracket 12 provided upon the adjacent upright face of the binder 3. While any form of bracket and adjustable connection with the wedge may be employed, a 10 satisfactory form of bracket is that of an arch, as shown in Fig. 3 of the drawings, the opposite ends of the arch portion being formed into ears which are secured to the binder 3 by suitable fastenings 13. The lower 15 end of the wedge 10 is received between the arch portion of the bracket and the adjacent face of the binder, and a set screw 14 extends through a horizontal slot in the binder and engages the wedge or with one of a 20 series of openings 16 in the lower end portion of the wedge. By this arrangement, the wedge may be driven upwardly until the shoe is rigid in a lateral direction and then the set screw 14 may be tightened to hold 25 the wedge in its adjusted position. The wedge is, of course, positioned after the shoe has been put in place and is driven upwardly through the open lower end of the groove 10, having first been introduced upwardly between the arch portion of the 30 bracket and the adjacent side of the binder 3.

It will, of course, be understood that the construction and arrangement of the lateral wedge for the shoe 7 is exactly the same as 35 for the wedge-shoe 8.

The wedge-shoe 8 has its inner upright face inclined with the inclination of the face 9 of the pedestal 2, and the flanges of the wedge-shoe embrace the pedestal in the 40 usual manner, as clearly shown in Fig. 2 of the drawings.

For the purpose of adjusting the wedge-shoe vertically, there is employed a wedge-bolt 17 which passes loosely through a vertical opening 18 in the binder 3 and has its 45 lower threaded end portion received through an arched or yoke-shaped bracket 19 secured to the underside of the binder 3. An upper nut 20 and a lower nut 21 are provided upon 50 the lower threaded portion of the bolt 17 and at opposite sides of the bracket 19, so that by manipulation of the nuts 20 and 21, the bolt may be adjusted vertically in opposite directions and thereafter held rigidly 55 upon the bracket by setting the nuts tightly against opposite sides of the bracket. The lower extremity 22 of the bolt is made polygonal so as to form a wrench-head. The upper threaded end of the bolt is received 60 within a bifurcation in the lower end of the wedge-shoe, said bifurcation consisting of a throat portion 23 opening through the bottom of the wedge-shoe and a larger seat portion 24. Within the seat portion 24 there is

a nut 25, and the upper threaded end of the 65 bolt 17 is engaged with this nut. By rotating the bolt 17, through the instrumentality of a wrench applied to the lower end of the bolt, said bolt may be turned within the nut 25 until the upper extremity of the bolt 70 has been thrust tightly against the top of the seat 24 and the nut 25 has been brought down tightly against the bottom wall of said seat, whereby a rigid connection will be maintained between the bolt and the wedge- 75 shoe.

It will here be explained that the only purpose of the nut 25 is to obtain a rigid connection between the bolt 17 and the wedge-shoe 8, as the vertical adjustment of 80 the wedge-shoe is obtained through the nuts 20 and 21. By this means, the bolt 17 may be rigidly supported upon the binder, and the wedge-shoe 8 rigidly supported upon the 85 bolt, whereby there will be no looseness between the wedge-shoe and the bolt, thus obviating the wear incident to such looseness.

Having thus described the invention, what 90 I claim is:—

1. A shoe for journal box pedestals comprising a back having a longitudinal flange, said flange having a longitudinal groove or channel in the inner face thereof, and a wedge-member adjustable longitudinally in 95 said groove or channel.

2. A shoe for journal box pedestals comprising a back having a longitudinal flange, said flange being provided with a longitudinal channel in the inner face thereof, the back of the channel being inclined longitudinally, and a wedge adjustable endwise in 100 said channel, said wedge having an inclined face lying against the inclined back of the channel.

3. A shoe for journal box pedestals comprising a back having a longitudinal flange, said flange having a longitudinal channel in the inner face thereof, a bracket for connection with the frame of the mounting of a journal box, and a wedge lying in the channel and having an adjustable connection with the bracket.

4. The combination with a pedestal and the binder of a journal box mounting, of a pedestal shoe having a longitudinal flange provided in its inner face with a longitudinal channel, and a wedge adjustably supported upon the binder and lying in the 115 channel.

5. A shoe for journal box pedestals provided with a seat within the shoe, an adjusting member having a threaded end which is rotatable in the seat, and a non-rotatable nut in the seat and receiving the threaded end of the adjusting member, said nut and the upper end of said adjusting member capable of being set rigidly against 125

the bottom and top of the seat respectively to form a rigid connection between the adjusting member and the shoe.

6. The combination with a pedestal and a binder, of a pedestal shoe having a seat therein, an adjusting bolt extending loosely through the binder and having a threaded upper end located in the seat of the shoe, a bracket depending from the binder, the bolt having a threaded portion passing loosely through the bracket, nuts carried by the threaded portion of the bolt at opposite sides of the bracket to clamp the latter and hold the bolt rigidly thereon, and a nut held 15 against rotation in the seat of the shoe, the upper end of the bolt being threaded and receiving said nut, the upper end of the bolt and said nut capable of being seated snugly against the top and bottom of the seat respectively by rotation of the bolt to 20

form a rigid connection between the shoe and the bolt.

7. The combination of a pedestal and a binder, of a flanged pedestal shoe, an adjusting bolt supported upon the binder and 25 connected to the shoe, and a wedge interposed between the shoe and the pedestal and supported upon the binder.

8. The combination of a pedestal and a binder, of a flanged shoe embracing the 30 pedestal, an adjusting bolt carried by the binder and connected to the shoe, the inner face of one of the flanges of the shoe having a longitudinal channel, and a wedge carried by the binder and lying in the channel and 35 against the pedestal.

ROBERT E. MAXWELL.
